UNITED STATES PATENT OFFICE

JAMES W. JENNINGS, OF PROVIDENCE, RHODE ISLAND, ASSIGNOR TO QUAKER SILVER COMPANY, OF ATTLEBORO, MASSACHUSETTS, A CORPORATION OF MASSACHUSETTS

DESIGN FOR A POWDER BOX

Application filed November 6, 1929. Serial No. 33,356. Term of patent 14 years.

To all whom it may concern:

Be it known that I, JAMES W. JENNINGS, a citizen of the United States of America, residing at 169 Calla Street, in the city of Providence, county of Providence, and State of Rhode Island, have invented a new, original, and ornamental Design for Powder Box, of which the following is a specification, reference being had to the accompanying drawing, forming a part thereof.

In said drawing:

Fig. 1 is a top plan view of a powder box showing my new design; and
Fig. 2 is a side elevation thereof.

I claim:

The ornamental design for a powder box substantially as shown.

Signed by me at Attleboro, in the county of Bristol and Commonwealth of Massachusetts this first day of November, 1929.

JAMES W. JENNINGS.
